UNITED STATES PATENT OFFICE.

SIMON E. SCHROEDER, OF NEWTON, IOWA, ASSIGNOR OF ONE-HALF TO ONE MINUTE MANUFACTURING COMPANY, OF NEWTON, IOWA.

AGITATOR FOR WASHING MACHINES.

Application filed March 24, 1924, Serial No. 701,429. Renewed March 9, 1925.

The object of my invention is to provide an agitator of simple, durable and inexpensive construction, especially designed for use in connection with machines for washing clothes, and comprising in its construction a series of flexible rubbing and agitating blades so constructed and arranged that they will impart a sufficient degree of agitation to the water within the tub, and also apply to the clothes being operated on an efficient rubbing action, due to the shape and flexibility of the agitator blades, whereby they will bend and adapt themselves to the contour of the mass of clothes being washed, and will, to a great extent, follow this contour and produce a rubbing action upon the clothes at all times; and

Further in this connection it is my object to provide an agitator of this class which will not tend to injure or tear the clothes being washed.

A further object is to provide means of simple, durable and inexpensive construction for detachably connecting the flexible blades to the agitator body, whereby they may be readily, quickly and easily removed or replaced, and at the same time firmly supported and connected to the agitator body when in use.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of an agitator embodying my invention.

Figure 2 shows a bottom view of same.

Figure 3 shows an enlarged detail sectional view on the line 3—3 of Figure 2.

Figure 4 shows a side elevation of an agitator embodying my invention, and shown in position engaging clothes being washed, to illustrate the manner in which the flexible agitator blades yield and conform to the contour of the mass of clothes; and

Figure 5 shows a sectional view on the line 5—5 of Figure 3.

Referring to the accompanying drawings, I have used the reference numeral 10 to indicate generally the agitator body. It is preferably disk shaped and made of alumi-

num or other material that will not rust or corrode when subjected to the uses for which agitators of this class are ordinarily employed. On its upper side is a socket 11 designed to receive an agitator shaft 12, and on its under surface there is a downwardly extending rib 13 around its circumference and a series of radial bracing ribs 14. Each of these radial bracing ribs is forked at 15 to provide two parallel downwardly extending ribs 16 extending to a point spaced apart from the center of the agitator body to the rib 13, thus forming a downwardly extended flange to receive and completely surround the upper ends of the agitator blades, hereinafter described.

The agitator blades are indicated generally by the reference numeral 17, and preferably made of relatively soft flexible rubber. Each has its upper edge shaped to enter between the ribs 16 and each blade has its outer edge extended downwardly and outwardly at 18, then curved downwardly and inwardly at 19 and then upwardly and inwardly at 20. Each blade also has its outer edge rounded, as shown at 21 in Figure 2.

For connecting the flexible blades to the agitator body I have provided in the upper edge of each blade two metal sleeves 22 open at both ends, and adjacent to the end of each sleeve within the agitator blade body, I have formed a transverse opening 23 to receive a nut 24. Bolts 25 are passed through the agitator body 10 and through the sleeve 22, and are then screwed into the nuts 24 which are held against rotation by the sides of the openings 23. These bolts are turned until the metal sleeves 22 are firmly clamped between the nut 24 at one end and the under surface of the body 10 at the other end.

Obviously, by this arrangement the agitator blades are firmly supported when in use and yet may be readily and quickly attached or detached when desired.

In practical use, it has been demonstrated that with my improved agitator, the water and suds within the tub will be agitated in a satisfactory manner, and as the blades are being alternately rotated in opposite directions over the surface of the clothes contained within the tub, they will yield and bend and adapt themselves to the change in contour of the surface of the clothes being

operated on, and that the soft flexible rubber will remove dirt from the clothes much more efficiently than metal or wood.

It has also been demonstrated that by use of flexible rubber blades of the character described, the wear and tear upon the garments being washed is reduced to a minimum.

What I claim is:

1. An agitator for washing machines comprising a reciprocal member, a plurality of radially extended flexible agitator members providing a substantially continuous yielding, rubbing and agitating surface, and means for attaching said agitator members to the reciprocating member.

2. An agitator for washing machines comprising a reciprocal disc, a series of radially arranged lobe fashioned flexible agitator members providing a substantially continuous yielding, rubbing and agitating surface, and means for attaching said agitator members to the disc.

3. An agitator for washing machines comprising a metallic body portion, a series of flexible blades, each blade being provided with openings at one side to receive nuts, metal sleeves extending from said openings to the adjacent edge of the blade, and bolts extended through the body, through said sleeves and into said nuts for connecting the blades to the body.

4. An agitator of the class described, com-

prising a body portion, a series of flexible blades extending radially relative to the body portion and secured to the under surface thereof, each blade having its outer edge extended downwardly and outwardly, then curved downwardly and inwardly and then upwardly and inwardly toward the center of the agitator body, said edges being rounded in transverse section.

5. An agitator for washing machines comprising a metallic disk shaped body portion having on its under surface a series of bracing ribs so shaped and arranged as to receive and completely surround the upper ends of agitator blades, and a series of agitator blades mounted in said ribs and held thereby against movement either laterally or inwardly and outwardly, and means for securing the blades to the body portion.

6. A washing machine agitator comprising a disc having a plurality of radial slots, and blades mounted in said slots to exert a yielding pressure on the clothes.

7. A washing machine agitator comprising a disc having a plurality of radial slots, and blades of resilient material having grooves to receive the edges of said slots and adapted to exert a yielding pressure on the clothes.

In testimony whereof I affix my signature.

SIMON E. SCHROEDER.
